TOY DOG FIGURE

Thomas Bowler, New York, N.Y., assignor to Canton
Cotton Mills, Canton, Ga., a corporation of Georgia

Filed Dec. 1, 1965, Ser. No. 3

Term of patent 14 years

(Cl. D34—2)

Fig. 4.

Fig. 5.

Fig. 6.

FIG. 1 is a perspective view of a toy dog figure, showing my new design;

FIG. 2 is a front elevational view thereof;

FIG. 3 is a rear elevational view;

FIG. 4 is a view of said figure from the right side;

FIG. 5 is a view from the left side; and

FIG. 6 is a top plan view.

I claim:

The ornamental design for a toy dog figure, substantially as shown.
